BLADE HOLDER

Everett C. Manthey and Arnold M. Thompson,
Chicago, Ill., assignors to Thompson Engineering & Mfg. Co., Chicago, Ill., a copartnership

Application October 19, 1949, Serial No. 122,234

2 Claims. (Cl. 30—336)

1

The present invention relates generally to holders. More particularly the invention relates to that type of holder which is designed as a medium or instrumentality for holding in an operating or useable position a blade, such as a razor blade, and comprises a handle and blade holding means at one end of the handle.

One object of the invention is to provide a blade holder of this type which is an improvement upon, and has certain inherent advantages over, previously designed holders and is characterized by the fact that it is both simple in design and highly efficient in operation or use.

Another object of the invention is to provide a blade holder of the type under consideration in which the handle is tubular and the blade holding means is in the form of a collet which is disposed for the most part within the tubular handle, consists of a handle housed shank and four coacting, resilient jaws having certain ends thereof connected to the shank and its other ends laterally enlarged and disposed exteriorly of the lower end of the handle, is adapted when shifted or slid downwards to a small extent relatively to the handle to have the jaws, due to their inherent resiliency, move apart into an open-blade receiving position, is further adapted when shifted upwards with respect to the handle to have the lower ends of the jaws contracted by engagement with the lower end of the handle so that they firmly grip the blade and hold the latter in its operating or useable position, and is so designed and constructed that, when not in use, the blade may be retained and fully sheathed or housed within the collet by first opening the jaws in response to downward shifting of the collet relatively to the handle, then sliding the blade longitudinally between the jaws so that it is fully covered by the jaws and finally shifting the collet upwards with respect to the handle so as to close the lower exposed ends of the jaws and thus retain the blade in place.

Another object of the invention is to provide in connection with a blade holder of the last mentioned character, an inverted cup-shaped cap which is slidably and rotatably mounted on the upper end of the tubular body and is so operatively connected to the collet by a longitudinally extending rod, one end of which is connected to the crosswall of the cap and the other end of which is connected to the upper end of the collet shank, that it serves when depressed or slid downwards relatively to the handle, to shift the collet downwards for jaw opening purposes.

Another object of the invention is to provide

2

a blade holder of the type and character under consideration in which the collet is retracted by a spiral compression spring which is disposed within the cup shaped cap and has one end thereof disposed adjacent the upper end of the tubular handle and its upper end in abutment with the crosswall of the cap.

A further object of the invention is to provide a blade holder of the type and character heretofore mentioned in which the rod constituting the operating connection between the cap and the collet is in the form of a screw rod and is so arranged and designed that it operates in connection with turning or rotation of the cap relatively to the handle to vary the loading of the spring.

A still further object of the invention is to provide a blade holder which is generally of new and improved construction and embodies such an arrangement and design of parts that it may be manufactured at a comparatively low cost.

Other objects of the invention and the various advantages and characteristics of the present blade holder will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective view showing a holder embodying the invention with a razor blade connected to the exposed ends of the jaws of the collet and extending lengthwise of the handle of the holder so that it is useable as a convention knife;

Figure 2 is a longitudinal section of the holder showing the collet and cap in their spring retracted positions, illustrating in full lines the position of the razor blade when sheathed or housed between the jaws of the collet in connection with non-use thereof and also illustrating by dash lines the manner in which the blade is capable of being connected to the lower ends of the collet jaws so as to extend transversely of the collet and be useable as a scraper;

Figure 3 is a longitudinal section showing the cap depressed so as to shift downwards the collet with respect to the tubular handle for jaw opening purposes; and

Figure 4 is a perspective of the four jaw collet.

The holder which is shown in the drawing constitutes the preferred form or embodiment of the invention and serves as a medium or instru-

mentality for holding a conventional injector variety razor blade 5 in an operative position for use as well as an inoperative or fully sheathed position when not in use. The blade 5 is shown in the drawing as being materially longer than it is wide and as having along one margin thereof only a cutting edge 6. It is contemplated, however, that the blade 5 may, if desired, have cutting edges along both side margins. As its component parts the holder comprises a tubular body 7, a collet 8, an inverted cup-shaped cap 9, a screw rod 10 and a spiral compression spring 11. It is adapted when not in use to be retained in the user's pocket and, as hereinafter described, is capable of holding the blade 5 in a position wherein it extends either lengthwise or crosswise of the handle.

The handle 7 is cylindrical and the internal diameter thereof as well as the external diameter is uniform from end to end. It is preferably formed of aluminum or any other suitable light, rigid metal and is open ended. It is contemplated that in certain uses and also when retained in the user's pocket the tubular handle will assume a substantially vertical position.

The collet 8 constitutes the holding and retaining means of the holder and consists of a shank 12 and four jaws 13. It is essentially of one-piece character as shown in Figure 4 and is disposed for the most part within the central and lower portions of the interior of the tubular handle 7. The shank 12 of the collet is cylindrical, embodies in its upper end a longitudinally extending centrally disposed screw threaded bore 14, and is of slightly less diameter than the inner periphery of the handle 7 in order that it is capable of sliding freely up and down in the handle. The four jaws 13 have the upper ends thereof formed integrally with the lower end of the shank 12 and are separated from one another by two longitudinally extending slots 15 which extend at right angles to one another. The lower ends of the jaws have laterally extending enlargements 16, the upper ends of which are upwardly tapered and the lower ends of which taper downwards and at all times are disposed exteriorly of the lower end of the tubular handle 7. The jaws are resilient and, due to the fact that they are separated by the slots 15, are capable of flexing towards one another into a closed position. When the collet 8 is slid or shifted upwards relatively to the tubular handle 7 the upper end of the laterally extending enlargements 16 coact with the lower end of the handle to cause the jaws to contract or move together into their closed position (see Figure 2). When the collet is shifted downwards with respect to the handle, as shown in Figure 3, the jaws 13, due to their inherent resiliency spread apart into an open or separated position. When the jaws are in the position last mentioned the slots 15 throughout their entire length are of greater thickness than the razor blade 5. The slots 15 are of greater length than the blade 5 in order that when the blade is not in use it may be inserted completely into one of the slots and held in a fully sheathed position between the jaws as shown in full lines in Figure 2. When it is desired to use the blade in a position wherein it extends lengthwise of the collet the collet is shifted downwards so as to open the jaws and the blade is permitted to slide downwards until it projects to any desired extent beyond the enlargements 16 at the lower ends of the jaws. Thereafter the collet is slid upwards with respect

to the handle in order to bring the lower ends of the jaws into clamped relation with the upper end of the blade 5 (see full line position of blade in Figure 1). In the event that it is desired to use the blade as a scraper (see dash line position in Figure 2) the blade is first removed from the jaws of the collet after opening of the jaws by sliding the collet downwards relatively to the handle. While the jaws are in their open position the blade is positioned transversely or crosswise of the lower ends of the jaws and is manipulated so as to bring its central portion into the lower end of one of the slots 15. Thereafter the collet 8 is shifted upwards with respect to the tubular handle in order to cause the lower ends of the jaws tightly to grip the central portion of the blade. When the blade is positioned as shown in Figure 1 and it is desired to sheath or house it between the jaws of the collet the collet is first shifted downwards relatively to the handle for jaw opening purposes. Thereafter the blade is slid upwards until it is disposed completely between the collet jaws 13. After upward sliding of the blade the collet is slid or shifted upwards with respect to the handle in order to close the lower ends of the jaws and thus retain the blade in place.

The inverted U-shaped cap 9 is mounted rotatably and slidably on the upper end of the tubular handle 7 and consists of a vertically elongated crosswall 17 and a circular depending skirt 18. The crosswall 17 of the cap has a longitudinally extending centrally disposed screw threaded bore 19, the upper end of which is closed and the lower end of which extends through the bottom face of the crosswall 17. The upper end of the skirt is formed integrally with the lower end of the cap crosswall 17 and the lower end of the skirt extends around the upper end of the tubular handle 7. A clip 20 for retaining the blade holder in the user's pocket is suitably connected to the crosswall 17 of the cap.

The screw rod 10 serves operatively to connect the cap 9 to the collet 8 so that when the cap is depressed, i. e., slid downwards with respect to the upper end of the handle, the collet 8 also moves downwards. The upper end of the screw rod 10 fits within the screw threaded bore 19 in the crosswall of the cap 9 and the lower end of the rod fits within the screw threaded bore 14 in the upper end of the shank 12 of the collet.

The spiral compression spring 11 extends around the central portion of the screw rod 10 and is disposed wholly within the depending skirt 18 of the cap 9. It serves as a medium for automatically retracting the cap and collet after downward shift of the latter for jaw opening purposes and has the upper end thereof positioned in abutment with the bottom face of the cap crosswall 17. The lower end of the spring abuts against the inner margin of a washer 21, the outer margin of which is seated on the upper end of the tubular handle 7. The inner margin of the washer embodies a depending annular flange 22 which fits within the upper end of the handle 7 and holds the washer against lateral displacement with respect to the handle. As shown in Figures 2 and 3, the central portion of the screw rod 10 extends through the hole or aperture in the washer. Compression or loading of the spring 11 is adjusted or varied by rotating the cap 9 relatively to the tubular handle 7. When the cap is turned so as to effect downward

feeding of the lower end of the screw rod 10 in the screw threaded bore 14 the compression or load of the spring is increased and when the cap is reversely turned so as to feed the lower end of the screw rod upwards with respect to the bore 5 14 the compression or loading of the spring 11 is reduced.

The herein described blade holder involves a novel design and arrangement of parts and is capable of being produced at a comparatively low cost. It effectively and efficiently fulfills its intended purpose and is characterized by the fact that it may be quickly and readily manipulated to effect clamping of the razor blade 5 in either of the blade's operative positions. Due to the design and construction of the collet 8 the blade, when not in use, may be fully or completely housed between the collet jaws. The component parts of the holder may be readily dismantled and this is attributable to the fact that the cap 9 is operatively connected to the collet 8 by the screw rod 10.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, a holder designed operatively to hold an elongated razor type blade and comprising a tubular handle adapted to be used in an upstanding position and having inwardly extending means at its upper end, a collet mounted for the most part within, and longitudinally slidable with respect to, the handle and consisting of a shank and a plurality of resilient coacting jaws disposed beneath the shank, separated by an elongated, longitudinally extending, blade-receiving slot and having the upper ends thereof connected to the lower end of the shank and their lower ends laterally enlarged and located exteriorly of the lower end of the handle, said collet being adapted when slid downwards relatively to the handle to have the enlarged lower ends of the jaws move away from the lower end of the handle and spread apart into an open position for receiving in the portion of the slot therebetween a part of the blade, and being further adapted when slid upwards relatively to the handle to have the lower enlarged ends of its jaws so move into engagement with the lower end of the handle so as to cause them to contract and grip said part of the blade, an inverted cup-shaped cap extending around, and slidably mounted on the upper end of, the handle and consisting of a crosswall and a depending continuous skirt, a rod extending between, and connected to, the crosswall of the cap and the upper end of the shank and adapted when the cap is slid downwards with respect to the handle correspondingly to slide the collet, a spiral compression spring extending around the upper end of the rod, disposed wholly within the skirt of the cap, having one end thereof abutting against said inwardly extending means and its other end abutting against the inner face of the cap crosswall, and arranged and adapted to urge the cap, rod and collet upwards with respect to the handle, said rod being connected to the upper end of the collet shank by a screw thread connection in order that rotation of the cap relatively to the handle serves to effect variation in the compression of the spring.

having one end thereof in abutment with the inwardly extending means and its other end in abutment with the inner face of the cap crosswall, and arranged and adapted to urge the cap, rod and collet upwards with respect to the handle.

2. As a new article of manufacture, a holder designed operatively to hold an elongated razor type blade and comprising a tubular handle 10 adapted to be used in an upstanding position and having inwardly extending means at its upper end, a collet mounted for the most part within, and longitudinally slidable with respect to, the handle and consisting of a shank and a plurality of resilient coacting jaws disposed beneath the shank, separated by an elongated, longitudinally extending, blade-receiving slot and having the upper ends thereof connected to the lower end of the shank and their lower ends laterally enlarged and located exteriorly of the lower end of the handle, said collet being adapted when slid downwards relatively to the handle to have the enlarged lower ends of the jaws move away from the lower end of the handle and spread apart into an open position for receiving in the portion of the slot therebetween a part of the blade, and being further adapted when slid upwards relatively to the handle to have the lower enlarged ends of its jaws so move into engagement with the lower end of the handle as to cause them to contract and grip said part of the blade, an inverted cup-shaped cap extending around, and mounted slidably and rotatably on, the upper end of the handle, consisting of a crosswall and a continuous depending skirt, a rod extending between, and connected to, the crosswall of the cap and the upper end of the shank, and adapted when the cap is slid downwards with respect to the handle correspondingly to slide the collet, and a spiral compression spring extending around the upper end of the rod, disposed wholly within the skirt of the cap, having one end thereof abutting against said inwardly extending means and its other end abutting against the inner face of the cap crosswall, and arranged and adapted to urge the cap, rod and collet upwards with respect to the handle, said rod being connected to the upper end of the collet shank by a screw thread connection in order that rotation of the cap relatively to the handle serves to effect variation in the compression of the spring.
